US0D1036206S

(12) **United States Design Patent** (10) Patent No.: **US D1,036,206 S**
(45) Date of Patent: ** Jul. 23, 2024

(54) **CRIMPING TOOL**

(71) Applicant: **Crimpit Group Ltd**, England (GB)

(72) Inventors: **Ian Peter Critchlow**, Warrington (GB);
Michael David Harper, Warrington (GB)

(73) Assignee: **Crimpit Group Ltd**, London (GB)

(**) Term: **15 Years**

(21) Appl. No.: **29/906,092**

(22) Filed: **Oct. 31, 2023**

(30) **Foreign Application Priority Data**

Jun. 1, 2023 (GB) 2308203
Jun. 9, 2023 (GB) 6288993

(51) **LOC (14) Cl.** **07-04**

(52) **U.S. Cl.**

USPC **D7/674**

(58) **Field of Classification Search**

USPC D7/672-677, 381, 693
CPC A47J 43/20; A23P 20/20; A23P 30/10;

(57) **CLAIM**

We claim the ornamental design for a crimping tool, as shown and described.

DESCRIPTION

FIG. 1 is a first perspective view of our design;
FIG. 2 is a front view of our design;
FIG. 3 is a rear view of our design;
FIG. 4 is a top view of our design;
FIG. 5 is a bottom view of our design;
FIG. 6 is a right side view of our design;
FIG. 7 is a left side view of our design;
FIG. 8 is a second perspective view of our design, showing the crimping tool partially open; and,
FIG. 9 is a third perspective view of our design, showing the crimping tool fully open.
The broken lines depict portions of the crimping tool that form no part of the claim.

1 Claim, 7 Drawing Sheets
